COLLINEAR SLEEVE TYPE ANTENNA ARRAY

Henry J. Riblet, Cambridge, Mass., assignor, by
mesne assignments, to the United States of
America as represented by the Secretary of the
Navy.

Application September 14, 1945, Serial No. 616,408

17 Claims. (Cl. 250—33.53)

1

My present invention relates to radio antennas and in particular to a radio antenna comprising one or more tubular-shaped radiators having radiation polarized in the direction of the axis of the said radiators.

My present invention contemplates a novel type of antenna element which may be used singly or in arrays in any known and usual fashion. Broadly, the invention comprises methods and means for producing radiating current on the surface of a metallic tube. These methods and means are hereinafter embodied in an antenna having substantially cylindrical radiation tubes which are of the order of one-half a wavelength long. However, it will be understood by those skilled in the art that the length and shape of these tubes are not limiting, but merely illustrative and that many other lengths and shapes will be able to be used.

It is accordingly an object of my invention to provide an antenna element comprising a metallic tube having radiating current on the outer surface thereof.

It is another object of my invention to provide a radio antenna comprising a plurality of such tubular antenna elements arranged in a fashion adapted to produce a pancake shaped beam having polarization substantially perpendicular to the plane of the beam.

It is a further object of my invention to provide novel feeding and supporting means for holding such tubular antenna elements on a coaxial or wave guide type of transmission line.

It is a still further object of my invention to provide such an antenna array that will be simple to construct and to adjust and tune.

Other objects and features of my invention will become apparent from a careful consideration of the following description when taken in connection with the drawing, the figures of which illustrate typical embodiments of the invention.

In the drawing,

Fig. 1 illustrates an antenna of my invention;

Fig. 2 illustrates a novel supporting means for the antenna elements of Fig. 1;

Fig. 2a is a diagrammatic illustration of the operation of the antenna of Fig. 1;

Fig. 3 illustrates an alternative shape for the antenna element of the antenna of Fig. 1;

Fig. 4 illustrates an antenna of my invention arranged to produce a pancake shaped beam;

Figs. 5 and 6 are cross sections of Fig. 4 taken along the lines V—V and VI—VI respectively; and

Fig. 7 is another antenna of my invention ar-

2

ranged for producing a pancake shaped beam.

In Fig. 1 a first cylindrical tube 1 and a second cylindrical tube 2 are arranged coaxially and linearly adjacent to each other with their mutually directed edges 3 and 4 spaced a small distance apart. A coaxial type transmission line 5, having an outer conductor 6 and an inner conductor 7 is disposed within these tubes 1 and 2, being coaxial therewith. A supporting spider 8, illustrated also in Fig. 2, comprising a collar 9 and three pairs of first and second fingers 10 and 11 respectively is adapted to fit snugly on the outer conductor 6 of the coaxial line 5. The pairs of fingers 10 and 11 respectively are arranged to support the two cylindrical tubes 1 and 2, respectively. In any pair of fingers 10 and 11, the two members of said pair are arranged axially with respect to the collar 9, and therefore with respect to the axis of the coaxial line 5. The first tube 1 is supported upon the three first members 10 of the pairs of fingers, while the second tube 2 is supported upon the second three members 11 of the pairs of fingers. The tubes 1 and 2 may be joined to the fingers 10 and 11 respectively by any known means, such as solder or bolting. Three holes 12 are provided in the collar 9, each hole being disposed between the members 10 and 11 of a pair of fingers. Similar holes 13 are provided in the outer wall 6 of the wave guide 5. The pairs of fingers 10 and 11, and the holes 12 and 13, respectively, are symmetrically disposed about the circumferential surface of the collar 9 and the outer conductor 6. Thus these holes and pairs of fingers are substantially 120° apart. Tabs 14 are provided on the inner edge 3 of the first cylindrical tube 1. These tabs 14 may be three in number and are preferably also symmetrically disposed about the edge 3. The first cylindrical tube 1 is so disposed upon the first three supporting fingers 10 that a tab 14 lies directly over a hole 12. The holes 12 and 13 are aligned so that a pair of holes 12 and 13 together form a passage into the wave guide 5 through the collar 9 and the outer wall 6. A tab 14 is disposed over each of these passages. A probe 15 is provided in each tab 14, being firmly mounted therein and therethrough and extending into the wave guide 5 through one of the aforementioned passages. The probes 15 terminate in the space between the outer conductor 6 and the inner conductor 7. These probes 15 are suitably in the form of screws and may be adjusted as to their penetration into the line 5 by turning in the usual manner.

The operation of the apparatus illustrated in Fig. 1 may best be understood with reference to the diagram of Fig. 2a, in which parts similar to parts of Fig. 1 are similarly numbered with the addition of the letter "a." Thus a transmission line 5a comprising two conductors 6a and 7a has two supports 10a and 11a upon one conductor 6a. Two radiating elements 1a and 2a are supported upon these supports 10a and 11a respectively. A passage "P" corresponding to that provided by two aligned openings 12 and 13 in Fig. 1 provides passage for a probe 15a attached to a tab 14a on the first radiator 1a. When energy is being carried in the transmission line 5a, electric currents will be excited in the probe 15a. Simultaneously, currents will be excited in the support 11a which currents will have a direction opposite to those excited in the probe 15a. Thus if we assume that currents are moving upward in the probe 15a, simultaneously current of equal magnitude will be moving downward in the support 11a. This is known as balanced feed. For this reason, the current in the radiators 1a and 2a will be in the same direction, or in phase, and the current strength curve in the two radiators combined 1a and 2a will be as shown by the curve "I." If each radiator 1a and 2a is one-half a wave length long, the combined radiators 1a and 2a together form a one wave length antenna.

It will be appreciated that the apparatus illustrated in Fig. 1 is substantially identical in operation to the apparatus illustrated diagrammatically in Fig. 2a. For example, if all the elements of the apparatus of Fig. 2a be rotated 360° about the conductor 1a of the line 5a, the apparatus of Fig. 1 will be formed. This rotation produces the solid members of Fig. 1 in place of line members as illustrated in Fig. 2. The supports 10 and 11 may be inserted in pairs as desired, as illustrated in the apparatus of Fig. 1. The radiating current will flow on the outer surfaces of the cylindrical tubes 1 and 2 and these tubes will then become cylindrically shaped radiators. The direction of polarization of the radiation will be longitudinal with respect to the longitudinal axis of the apparatus of Fig. 1. The radiation should be substantially non-directional in the plane perpendicular to the said axis. Directivity of the full wave double dipole of Fig. 1 will be had in a direction perpendicular to the aforementioned axis and a sort of doughnut-shaped beam will be produced by the antenna.

Fig. 3 illustrates an alternative form of tube 17 that may be used in place of the cylindrical tubes 1 and 2 if desired. Tabs 14 may be of any number desired, the number and disposition of the said tabs 14 being preferably determined empirically to afford the desired pattern about the antenna. The tube 17 is streamlined in shape, such a shape being desired if the antenna is to be airborne.

Referring now to Figs. 4, 5, and 6, there is there illustrated an antenna comprising a plurality of substantially cylindrical radiators 21 and 22 like the radiators 1 and 2 of Fig. 1 arranged coaxially and linearly to produce a beam having narrow directivity in a direction substantially perpendicular to the longitudinal axis of the apparatus, and having substantially no directivity about the apparatus in a plane perpendicular to the said axis. This is known as a pancake beam. The cylindrical radiators 21 and 22 are alternately placed in a linear array. Again a coaxial type transmission line 5, comprising an outer wall 6 and inner con-

ductor 7, is located concentrically within the radiators 21 and 22. The radiators 22 are substantially identical to the radiator 2 of Fig. 1. The radiators 21, however are fed at both ends by probes 15 identical to the probes 15 of Fig. 1. Tabs 14 are provided at both ends of each radiator 21. Three tabs 14 are provided at each end of a radiator 21 and are symmetrically disposed thereabout. However, the tabs at one end are displaced circumferentially 60° from the tab at the opposite end. This provides for more uniform dispersion, or lesser directivity, in the plane about the axis of the apparatus. The feeding of the probes 15 in the apparatus of Fig. 4 is accomplished in an identical manner to the feeding of the probes 15 in the apparatus of Fig. 1. The cross sectional views of Figs. 5 and 6 illustrate the relationship between an array of probes at one end and an array of probes at the other end of a radiator 21. A spider 8 (not shown in Fig. 4) is provided between each two adjacent radiators 21 and 22, respectively, for the purpose of supporting these radiators in identical fashion as the radiators 1 and 2 of Fig. 1 are supported. Holes 12 and 13 are provided where appropriate in the spider 8 and the outer conductor 6 in order to permit the passage of the probes 15 into the transmission line 5.

The current distribution I' on the outer surface of the radiators 21 and 22 is shown in Fig. 4 as it may appear instantaneously. It will be noted that each half wave of the current is in phase with a neighboring half wave. This results from the fact that each of the radiators 21 having probes, is driven at both ends. Since these radiators are substantially one-half wave length long, the probes at opposite ends are driven in 180° phase opposition. Thus when the current in probes at one end is moving outward from the transmission line to the radiator 21, the current in the probes at the other end will be moving inward from the radiator 21 to the transmission line. This will cause the current at one end of a radiator 21 to move in the same direction as the current at the other end of the said radiator at any one instant. Since, as shown in Fig. 2a the direction of the current at the end of a radiator not having a probe is the same as the direction of the current at the adjacent end of a radiator having a probe, it follows that the current on the surfaces of all the radiators 21 and 22 in the array will at any one instant have the same direction, and hence all the radiators will be driven in the same phase. For this reason, the beam produced by the antenna of Fig. 4 will have directivity in directions perpendicular to the axis of the array. Since, however, the radiators are substantially cylindrical and since the feeding probes are symmetrically disposed thereabout and alternately staggered, the beam will be substantially non-directional in the plane perpendicular to the axis of the array. Such a beam is known as a pancake beam.

The apparatus illustrated in Fig. 7 is another embodiment of my invention for producing a beam similar to that produced by the apparatus of Fig. 4. Substantially cylindrical half-wave radiators 31 and 32 respectively are collinearly and coaxially aligned in a manner similar to the radiators 21 and 22 of Fig. 4. Alternate radiators 31 have probes 15 at both ends thereof supported in tabs 14'. As in the case of the radiators 21 of the apparatus of Fig. 4, the radiators 31 of the apparatus of Fig. 7 are driven by probes 15 located at both ends thereof. Thus the currents

at each end of a radiator 31 are going in the same direction at any one instant. Each radiator 31 or 32 is held by a support 33 near its center point upon the outer wall 6 of the transmission line 5. The support 33 effectively forms a short circuit between the radiator 31 or 32 and the outer wall 6. Since each radiator 31 or 32 is substantially one-half wave length long, the space between a radiator 31 or 32 and the outer wall 6 may be considered to form two short circuited substantially quarter wave chokes 34 in each radiator. The lengths of these chokes are not critical however, and the supports 33 may be thickened if desired, without harmful effect on the current flowing on the outer surfaces of the radiators 31 and 32. The current wave at any one instant I'' comprises a series of half waves, all in phase with each other. Since, however, the radiators 31 are supported at their centers instead of at their ends, the current waves in the current I'' each have their high current point near the support 33 rather than near the probes 15 as in the apparatus of Fig. 4. Thus in Fig. 7 probes 15 feed the radiator 31 at high voltage points. The beam of this apparatus is, however, substantially identical to the beam of the apparatus of Fig. 4, namely a pancake beam lying in a plane substantially perpendicular to the axis of the apparatus.

Although I have shown radiating elements of my invention in antennas for producing beams having a pancake shape, it will be appreciated by any one skilled in the art that radiating elements constructed in accordance with my invention may be arranged in any known type of array to produce any type of beam desired. Further, the tubular radiators of my invention may have various cross sectional shapes without departing from the invention.

What is claimed is:

1. A radio antenna comprising a plurality of collinearly disposed tubular substantially half wave length long radiators, a transmission line, and at least one probe at each end of each alternate radiator, said probes at opposite ends of each alternate radiator being coupled to said transmission line in such fashion as to be fed in phase opposition by the field thereof.

2. A radio antenna comprising a linear array of substantially cylindrical coaxially disposed substantially half wave length long radiators, a transmission line for feeding said radiators substantially coaxially disposed therein, and three probes substantially symmetrically disposed about opposite ends respectively of each alternate radiator, said probes being inwardly directed into said transmission line and coupled thereto in such fashion that said probes at opposite ends of each alternate radiator are respectively fed in phase opposition by the field thereof.

3. The apparatus of claim 2 in which said probes are attached to said opposite ends at substantially symmetrically disposed circumferential points, each of the points at one end being circumferentially displaced substantially 60 degrees from the corresponding points at the other end.

4. A radio antenna comprising first and second adjacent linearly coaxially disposed substantially cylindrical substantially half wave length long radiators having adjacent edges, three axially projecting tabs on said first radiator symmetrically disposed about its adjacent edge, a coaxial transmission line having inner and outer conductors disposed substantially concentrically

within said radiators, said outer conductor having three symmetrically circumferentially disposed openings therein arranged one beneath each of said tabs, a supporting spider for holding said radiators on said line comprising a substantially cylindrical collar adapted to fit snugly on said outer conductor and three pairs of first and second outwardly projecting fingers on said collar symmetrically disposed thereabout, said first and second members of each of said pairs being axially disposed, three openings in said collar disposed one between the members of each of said pairs, said openings in said outer conductor and collar being mutually aligned in pairs to form three respective passages into said line through said collar, said radiators being supported at said adjacent edges one upon said first and the other upon said second fingers, said tabs being each aligned axially with a pair of first and second fingers, and three probes mounted one in and through each of said tabs and extending through the therebeneath disposed passage into said line and terminating in the space between said inner and outer conductors.

5. A radio antenna comprising first and second spaced radiators having adjacent ends, a coaxial transmission line having inner and outer conductors, conductive support means for securing each of said radiators, at its end adjacent the other of said radiators, to said outer conductor, a probe secured at that end of said first radiator adjacent to said second radiator, said outer conductor being formed with an opening for receiving said probe, the free end of said probe terminating in the space between the inner and outer conductors of the transmission line, whereby in phase currents are caused to flow in said radiators due to the excitation of said transmission line.

6. A radio antenna comprising a linear array of substantially cylindrical, substantially half-wave length long, radiators, a transmission line having at least an outer conductor for feeding said radiators, conductive means substantially at the center of each of said radiators securing said radiators to said outer conductor, at least one probe at each end of each alternate radiator, said outer conductor being formed with openings for receiving said probes, said probes being inwardly directed into said transmission line and coupled thereto.

7. A radio antenna comprising two elongated, spaced, collinear, tubular radiators, a transmission line extending through said tubular radiators, conductive means securing said radiators at their adjacent ends to said transmission line, and at least one probe secured to one of said radiators at the end thereof adjacent said other radiator, said probe being coupled to said transmission line.

8. A radio antenna comprising two elongated, spaced, collinear, tubular radiators, a coaxial transmission line extending through and spaced from said radiators, conductive means securing said radiators at their adjacent ends to the outer conductor of said transmission line, and at least one probe secured to one of said radiators at the end thereof adjacent said other radiator, said probe extending into space between the conductors of said coaxial transmission line.

9. Apparatus, as defined in claim 8, wherein each of said radiators is a half wave length long.

10. A radio antenna comprising an array of axially spaced, axially aligned radiators, a transmission line for conducting energy in the direction defined by said radiators, conductive means securing said radiators at their adjacent ends to

said transmission line, and at least one conductive probe secured to each alternate radiator at each end thereof adjacent an end of another radiator, each of said probes being coupled to said transmission line.

11. A radio antenna comprising, an array of spaced, collinear, tubular radiators, a transmission line extending through and spaced from said radiators, conductive means securing said radiators at their adjacent ends to said transmission line, and at least one conductive probe secured to each alternate radiator at each end thereof adjacent an end of another radiator, each of said probes being coupled to said transmission line.

12. Apparatus, as defined in claim 11, wherein each of said radiators is one-half wave length long and wherein said transmission line is coaxially disposed within said radiators.

13. A radio antenna comprising an array of spaced, adjacent, collinearly disposed, substantially cylindrical, substantially half wave length long radiators, alternate radiators being formed with a plurality of axially projecting tabs symmetrically disposed about each end thereof adjacent another radiator, a coaxial transmission line having inner and outer conductors disposed substantially concentrically within said radiators, said outer conductor being formed with openings arranged one beneath each of said tabs, conductive spiders supporting said radiators at their adjacent ends on said line, each of said spiders comprising a substantially cylindrical collar fitted snugly on said outer conductor and a like plurality of pairs of outwardly projecting fingers on said collar symmetrically disposed thereabout, said collar having openings formed therein one between each of said pairs of fingers, said openings in said outer conductor and said collars being mutually aligned to form passages through each of said collars into said line, said radiators being supported at adjacent ends thereof so that one end of one radiator is supported upon one of each of said pairs of fingers and the adjacent end of the adjacent radiator is supported upon the other of each of said pairs of fingers, said tabs each being radially aligned with a pair of fingers, and a like plurality of probes mounted one in and through each of said tabs and extending through the therebeneath disposed passage into said line and terminating in the space between said conductors.

14. Apparatus, as defined in claim 13, wherein said plurality is equal to three, each tab of each group of three circumferentially disposed tabs being circumferentially displaced by 60° from the corresponding tabs of any adjacent group of circumferentially disposed tabs.

15. A radio antenna comprising an array of collinear, tubular radiators arranged end to end, a transmission line extending through and spaced from said radiators, conductive means for each of said radiators disposed in a region thereof intermediate its ends and conductively securing said radiator to said transmission line, and at least one conductive probe secured to each alternate radiator at each end thereof adjacent an end of another radiator, each of said probes being coupled to said transmission line.

16. Apparatus as in claim 15 wherein each of said radiators is one-half wave length long.

17. A radio antenna comprising an array of adjacent, linearly, coaxially disposed, substantially cylindrical, substantially half wave length long radiators, alternate radiators being formed with axially projecting tabs symmetrically disposed about each end thereof adjacent another radiator, a coaxial transmission line having inner and outer conductors disposed substantially concentrically within said radiators, said outer conductor being formed with a plurality of openings arranged one beneath each of said tabs, a support for each radiator located substantially at the longitudinal center thereof and short-circuiting said outer conductor and said radiator at said center, and a plurality of probes mounted one in and extending through each of said tabs and extending through the opening in the outer conductor therebeneath and into said line, each of said probes terminating in the space between said conductors.
